UNITED STATES PATENT OFFICE.

CHARLES J. COOPER, OF MOLINE, ILLINOIS.

DESIGN FOR A HARNESS-BUCKLE.

45,225.

Specification for Design.

Patented Feb. 10, 1914.

Application filed December 3, 1913. Serial No. 804,513. Term of patent 14 years.

● *To all whom it may concern:*

Be it known that I, CHARLES J. COOPER, a citizen of the United States, residing at Moline, in the county of Rock Island and State of Illinois, have invented a new, original, and ornamental Design for Harness-Buckles, of which the following is a specification, reference being had to the accompanying drawing, forming part thereof.

In the drawing, Figure 1 is a perspective elevation of the buckle as viewed from the

upper side thereof, showing my new design. Fig. 2 is a perspective elevation of the same buckle as viewed from the under side thereof, showing my new design.

I claim—

The ornamental design for a harness buckle, as shown.

CHARLES J. COOPER.
